UNITED STATES PATENT OFFICE.

HORACE GUERNSEY WILLIAMS, OF ST. DAVIDS, PENNSYLVANIA.

IMPACT-TOOL.

SPECIFICATION forming part of Letters Patent No. 554,849, dated February 18, 1896.

Application filed May 7, 1895. Serial No. 548,404. (No model.)

To all whom it may concern:

Be it known that I, HORACE GUERNSEY WILLIAMS, a citizen of the United States, residing at St. Davids, in the county of Delaware and State of Pennsylvania, have invented certain new and useful Improvements in Impact-Tools, of which the following is a specification.

My invention relates in general to that class 10 of impact-tools, particularly rock-drills, which are operated by compressed air, steam, or other motive fluid under pressure, in which the tool is connected with the rod of a plunger adapted to reciprocate within a cylinder 15 to the respective ends of which the motive fluid is alternately admitted behind and in front of the plunger, and relates more particularly to that class of rock-drills in which are embodied a rifled rod and ratchet for occasioning the partial rotation of the plunger and drill upon their return stroke.

My invention has for its object the construction of a tool of the foregoing class mechanically simple and inexpensive, in which 25 the number of parts is reduced to a minimum, and in which provision is made for adequate and instantaneous supply and uniform and instantaneous exhaust.

A tool embodying a preferred form of my 30 improvements is represented in the accompanying drawings and hereinafter described, the particular subject-matter claimed as novel being hereinafter definitely specified.

In the drawings, Figure 1 is a top plan view 35 of the tool complete; Fig. 2, a central vertical longitudinal side sectional elevation through the tool of Fig. 1 in the plane of the dotted line *w w* on said figure, and sight being taken in the direction of the arrows applied to said line. Fig. 3 is a fragmentary sectional plan in the planes of the dotted lines *x x* of Fig. 6 through such portion of the cylinder as serves to illustrate the preferred common connection of the front and 45 rear exhaust-ports with the outlet to the atmosphere by means of the exhaust passage-way *a*⁷. Fig. 4 is a front elevational view of the tool represented in Figs. 1 and 2, section being taken through the plunger-rod in the 50 plane of the dotted line *y y* and sight being taken in the direction of its arrows. Fig. 5 is a rear end elevational view of the tool rep-

resented in Fig. 1. Fig. 6 is a transverse vertical sectional elevation through the tool of Figs. 1 and 2 in the plane of the dotted line *z z*, and sight being taken in the direction of its arrows. Fig. 7 is a view similar to Fig. 6, with the section taken in the plane of the dotted line *u u* in Figs. 1 and 2. Fig. 8 is an inside face view of the back head of the cylinder removed in order to exhibit the ratchet-wheel of the rifled rod and the spring-controlled pawls applied thereto. Fig. 9 is a side elevation of the rifled rod and ratchet-wheel removed from the cylinder. Fig. 10 is 65 an end view of the front end of the rifled rod, and Fig. 11 an end view of the ratchet-wheel. Fig. 12 is a transverse vertical section through the rear end portion of the plunger and through the rifled nut and rod in the plane 70 of the dotted line *s s* of Fig. 2.

Similar letters of reference indicate corresponding parts.

A represents a cylinder within which the plunger is adapted to reciprocate and which 75 is of any preferred exterior configuration and formed of any suitable material.

a is the front head of said cylinder, and *a*^x the back head, the said heads being conveniently retained in place by the tie-bars *a'* *a*², 80 and being formed and applied in any usual manner.

*a*³ is the alley for the feed-screw usual in devices of this character, and conveniently formed integral with the casting of the cylinder. 85

*a*⁴ is the thrust-nut for the feed-screw.

A' is the fluid-inlet port of the cylinder, an annular internally-open passage-way formed wholly in the walls of the cylinder and completely circumscribing the same, as shown in Figs. 2 and 6. 90

*A*² is the inlet-pipe through which the motive fluid is led into the annular inlet-port *A'*. The inlet-port is preferably formed approximately near the central portion of the cylinder. 95

*a*⁵ is the front exhaust-port and *a*⁶ the rear exhaust-port of the cylinder. The rear exhaust-port, and preferably also the front exhaust-port, are formed wholly in the walls of the cylinder as an annular internally-open passage-way completely circumscribing said cylinder, and the said ports are respectively 100

disposed intermediately between the inlet-port and the front head on the one hand and the inlet-port and the back head on the other. Each of said exhaust-ports is in communication with the atmosphere, preferably through the intervention of a common exhaust passage-way a^7 , Figs. 3 and 6, formed in the cylinder-casting and leading to an outlet-pipe A^8 .

To prevent weakening of the walls of the cylinder, the inlet-port and both of the exhaust-ports, when both are circumferentially extended, are conveniently formed within external circumferential enlargements of the casting of the cylinder, as will be understood by reference to Figs. 1 and 2 of the drawings.

a^8 is a buffer of any preferred construction disposed within the front end of the cylinder and bearing against the front head. The front head is suitably chambered to receive any preferred form of packing a^9 to which the motive fluid may have access, either by leakage around the plunger-rod or by passing through the apertures in the buffer.

B is a plunger, preferably of such relative length, proportionate to the length of the cylinder, as is represented in the drawings, and which is adapted to reciprocate within the cylinder.

b is the plunger-rod, which protrudes through the packing-box of the front head of the cylinder, and is exteriorly thereto provided with a coupling b^x of any preferred character, by means of which the drill or other impact-tool b' is connected with it.

b^3 is the plunger proper contains a preferably axial passage-way or bore, which I term the "plunger supply-port" b^3 , and which extends longitudinally from the front portion of the plunger to and through the rear end thereof.

b^3 is an opening through the upper walls of the plunger supply-port b^2 , which I term the "plunger inlet-port." Through this port motive fluid admitted to the inlet-port A' of the cylinder gains access to the hollow interior or supply-port b^2 of the plunger.

C is a rifled rod of a character usual in tools of this class, except that it is preferably flattened at its sides, as indicated in Figs. 9 and 10. This rod, as is usual, extends rearwardly to and is connected with a ratchet-wheel c adapted to a socket a^{10} , formed within the back head a^x of the cylinder, as shown in Figs. 2 and 8, and is contained within the supply-port b^2 of the plunger.

B^x is a rifled nut, screwed into or otherwise connected with or formed as a part of the rear end portion of the plunger. This nut preferably possesses substantially the form represented in Fig. 12 in order that, while it is adapted to the rod in such manner as to occasion the usual rotation of the plunger, it yet is so formed, longitudinally channeled out, or enlarged upon one or both sides of the rod as to form what may be termed a "nut-port," or "nut-ports" b^4 , through which the motive fluid entering the plunger supply-port

may pass to beyond the rear end of the plunger.

The nut port or ports are in effect simply a fluid-port extending throughout the length 70 of the nut.

c' are ratchet-pawl, which act in the usual manner upon the ratchet-wheel of the rifled rod, but which, as shown in Fig. 8, are formed with solid cylindriform heads c^2 adapted to 75 cylindriform seats c^3 formed in the substance of the back head a^x of the cylinder, and within which seats are contained bushings c^4 possessing the form of segments of a hollow cylinder, and which are adapted to be easily 80 introduced into and removed from the said pawl-seats c^3 .

c^5 are U-springs adapted to be sprung within elliptical seats c^6 formed in the substance of the back head, and which are operative 85 upon the pawls in the usual manner to retain them in contact with the ratchet-teeth.

By resort to the special construction of pawls, springs, seats and bushings, above set forth, I greatly simplify the ratchet mechanism while rendering it more durable.

b^5 is what I for convenience term the "plunger exhaust-port," the same being, as clearly shown in Figs. 2, 6, and 7, a passage-way formed longitudinally in the substance of the plunger beneath, but not in communication with the axial cavity therein, which I have termed the "plunger supply-port" b^2 . This plunger exhaust-port b^5 opens through the front end of the plunger, as shown in Fig. 2, 100 and extends rearwardly to a blind ending conveniently in the neighborhood of the rifled nut.

b^6 , Figs. 2 and 7, are vent-ports leading from the plunger exhaust-port b^5 through the substance of the lower walls of the plunger. One or a plurality of these vent-ports may be employed, and their venting area is calculable with reference to the desired exhaust.

The vent-ports themselves are, for convenience of manufacture, formed in a segmental plate b^7 dovetailed into the plunger proper, as shown in Figs. 6 and 7, and forming, when in place and permanently secured, a portion of the lower walls of the plunger, and constituting a mere expedient of manufacture 115 to facilitate the formation of the plunger exhaust-port b^5 .

b^8 are plunger packing-rings of any preferred character, circumscribing the plunger and serving to make it tight within the cylinder.

Such being a description of a tool conveniently embodying my improvements, its operation will be readily understood.

Assuming the plunger in the position represented in Figs. 1 and 2, and motive fluid admitted through the inlet-pipe A^2 into the circumferential inlet-port A' , it is obvious that said fluid will pass through the plunger inlet-port b^3 into the plunger supply-port b^2 , 125 and thence through the nut-ports b^4 in the rifled nut into the space between the back

head of the cylinder and the back end of the plunger, and therein, by its expansive action, will occasion the forward movement of the plunger. It is further obvious that said forward movement of said plunger will be made possible by the fact that the front exhaust-port a^5 is, for the time being, through the exhaust passage-way a^7 and the outlet-pipe A^3 , in communication with the atmosphere, and 5 that, therefore, the lead has been given to the exhaust in front of the plunger. It will be further apparent that when the plunger shall have completed its forward movement its rear end will have passed beyond or to the front 10 of the rear exhaust-port a^6 , theretofore occluded by it, so as, through said port, the exhaust-passage a^7 and the outlet-pipe A^3 , to give the lead to the exhaust to the rear of the plunger. It will, moreover, be apparent that 15 when the plunger has reached its said forward position the vent-ports b^6 from the plunger exhaust-port b^5 , theretofore occluded by the cylinder, will be in registry with the lower portion 20 of the inlet-port A' , and will thereby permit of the influx of the motive fluid into and through the said plunger exhaust-port b^5 to the space for the then time being existing between the buffer and the front end of the plunger, the front exhaust-port a^5 being at 25 the same time closed by the plunger, with the result that the rear exhaust-port a^6 , being in communication with the atmosphere, the plunger will be driven backward until it has resumed its rear or first position, whereupon 30 the parts having all resumed their original positions, the operation described will be repeated, and the plunger again driven forward to be again driven back.

In the practical operation of the tool, it results that so long as the supply of motive fluid is continued, the plunger will continue to reciprocate, and will upon each return stroke receive from the rifled-rod contrivance the usual movement of rotation.

Having thus described my invention, I claim and desire to secure by Letters Patent—

1. An impact-tool in which are combined, a cylinder having independent inlet and exhaust ports, a plunger adapted to reciprocate within said cylinder and embodying a longitudinally-extending supply-port and an inlet-port into said supply-port, a ratchet-controlled rifled rod connected with the cylinder and extending within the plunger supply-port, and a rifled nut applied to the plunger and rifled rod and embodying a port extending throughout its length, and communicating with the plunger supply-port, substantially as and for 55 the purposes set forth.

2. An impact-tool in which are combined, a cylinder having an independent circumferentially-extending inlet and two exhaust ports, a plunger adapted to reciprocate within said cylinder and embodying a longitudinally-extending supply-port and an inlet-port into 60 said supply-port, and also an independent

longitudinally-extending exhaust-port having a vent-port, a ratchet-controlled rifled rod connected with the cylinder and extending within the plunger supply-port, and a rifled nut applied to the plunger and rifled rod, and embodying a port extending throughout its length and communicating with the plunger supply-port, substantially as and for 75 the purposes set forth.

3. A cylinder for the reciprocating plunger of an impact-tool, in the walls of which are embodied an approximately central circumferentially-extending inlet-port in communication with a source of motive-fluid supply, and also a pair of exhaust-ports respectively intermediate between the inlet-port and the heads of the cylinder and in communication with the atmosphere, in combination with a 80 plunger adapted to be reciprocated within said cylinder, and embodying a longitudinally-extending supply-port and an inlet-port into said supply-port, a ratchet-controlled rifled rod connected with the cylinder and 85 extending within the plunger supply-port, and a rifled nut applied to the plunger and rifled rod and embodying a port extending throughout its length and communicating with the plunger supply-port, substantially 90 as set forth.

4. A cylinder for the reciprocating plunger of an impact-tool, in the walls of which are embodied an approximately central circumferentially-extending inlet-port in communication with a source of motive-fluid supply, and also a pair of exhaust-ports respectively intermediate between the inlet-port and the heads of the cylinder and in communication with the atmosphere, in combination with a 100 plunger adapted to be reciprocated within said cylinder, and embodying a longitudinally-extending supply-port and an inlet-port into said supply-port, and also an independent longitudinally-extending exhaust-port 105 having a vent-port, a ratchet-controlled rifled rod connected with the cylinder and extending within the plunger supply-port, and a rifled nut applied to the plunger and rifled rod and embodying a port extending throughout its length and communicating with the plunger supply-port, substantially 110 as set forth.

5. An impact-tool in which are combined, a cylinder having inlet and exhaust ports, a 115 plunger embodying a longitudinally-extending supply-port and provided with a rifled nut having a port extended throughout its length and communicating with said plunger supply-port, and a ratchet-controlled rifled rod extending within the plunger supply-port and engaged within said rifled nut, substantially as and for the purposes set forth.

6. An impact-tool in which are combined, a cylinder the back head of which embodies 120 a socket for a ratchet-wheel, cylindric seats for ratchet-pawls, and elliptical seats for U-springs, segmental hollow cylindric bushings adapted to said pawl-seats, ratchet-pawls

formed with cylindric heads adapted to said bushing - provided pawl-seats, **U** - springs adapted to said spring-seats, and a rifled rod-provided ratchet-wheel adapted to said 5 socket, substantially as and for the purposes set forth.

In testimony that I claim the foregoing as

my invention I have hereunto signed my name this 30th day of April, A. D. 1895.

HORACE GUERNSEY WILLIAMS.

In presence of—

J. BONSALL TAYLOR,

Wm. C. STRAWBRIDGE.
